UNITED STATES PATENT OFFICE.

NORMAN B. HURD, OF NEW BRITAIN, CONNECTICUT, ASSIGNOR TO THE AMERICAN HARDWARE CORPORATION, OF NEW BRITAIN, CONNECTICUT, A CORPORATION OF CONNECTICUT.

LOCK.

Application filed March 26, 1924. Serial No. 701,981.

To all whom it may concern:

Be it known that I, NORMAN B. HURD, a citizen of the United States of America, residing at New Britain, Connecticut, have 5 invented a new and useful Lock, of which the following is a specification.

My invention relates to a lock, particularly, though not exclusively, adapted for clothes locker doors.

10 It is a general object of my invention to provide a simple form of lock, which may be opened by key means and which may be locked by other manual means.

15 It is a more specific object to provide a lock for a locker door or the like in which the locking bolt is retracted by key means, and which may be released by other manual means.

20 It is another object to provide a lock for a dead bolt on a door, wherein the locking bolt may be retracted by key means and held in that position, and which may be released to lock the dead bolt by other manual means.

25 It is a further object to provide a highly simplified form of lock for a locker door or the like.

Briefly stated, a preferred form of my invention includes what may be termed a locking plate controlling one or more dead bolts and manually operable by the usual handle on the outside of a locker door or the like. The locking plate and its dead bolt or bolts are adapted to be held in locked position by my improved locking means, and the locking plate is further adapted to so unlatch or trip the locking bolt that the same may be moved forwardly to lock the locking plate and dead bolts in place. The improved locking bolt means is retracted by key-actuated means, and, when retracted, is acted upon by a spring so as to latch the same in retracted position. The locking plate, when fully retracted, springs or trips the locking bolt so as to release it from its latched position, so that when the locking plate is moved to locked position the locking bolt moves forwardly to lock the locking plate in position.

50 In the drawings which show, for illustrative purposes only, a preferred form of the invention—

Fig. 1 is a fragmentary view of the front of a locker door or the like, parts being broken away to illustrate features of my 55 invention;

Fig. 2 is a perspective view of my improved lock, the parts being relatively separated to better illustrate the construction;

Fig. 3 is a rear view of parts shown in 60 Fig. 1;

Fig. 4 is a side elevation of a so-called locking plate.

In said drawings, 5 indicates a portion of a locker door or the like abutting the usual 65 jamb 6. A member, which I may term a locking plate 7, is pivoted to the door 5 and is operated by the usual handle 8 on the outside of the door. The plate 7 may carry a dead bolt 9 and, if desired, may also carry 70 links 10—11 for throwing other dead bolts, if such additional bolts are desired. Stop pins 12—13 may be provided for limiting the oscillation of the locking plate 7. In the form shown the locking plate has a 75 detent in the form of an upstanding flange 14, with an abrupt shoulder 15, for a purpose to be hereinafter described.

A lock case 16 is secured on the door, preferably at the rear thereof, and, in the form 80 shown, has a guide or passageway 17 for a part of a locking bolt 18, which is adapted to slide thereon. One of the parts, in the present instance the lock case, may have a slot 19 for the reception of a pin 20 carried by the locking bolt 18 which, while pivoting the same, permits sliding movement between the locking bolt and the lock case. In the form shown a cylinder lock 21 is secured to the lock case, and the plug 22 extends into 85 the passageway 17 and into a suitable recess or aperture 23 in the locking bolt 18. Means, such as a pin 24 carried by the plug 22, is adapted to fit in a part of the recess and acts against the surface 25 for retracting the 90 locking bolt when the plug is actuated by means of a key from the outside of the door.

The forward end 26 of the locking bolt, and the part constituting the locking means proper, is offset relatively to the main plate 18 thereof. A guide notch 27 is provided in one side of the offset connecting portion, and at the opposite side there is a second guide notch 28. At the rear of the forward 100

portion 26 there may be a lug 29 at one side for the reception of one end of a coil spring 30. The lock case in the present form is provided with a pocket 31, for the reception 5 of part of the end 26 of locking bolt and part of the offset connecting portion. The edges 32-33 of the plate forming a part 10 of the passageway 17 act as guides and extend into the guide slots 27-28 on the locking bolt. One side of this plate is cut back as at 34, so as to leave a sharp shoulder 35 to act as a latch for the locking bolt, as will be later described. The spring 30, in the 15 form shown, fits in the pocket 31 and is suitably confined in a recess therein.

When the parts are assembled the main plate portion of the locking bolt 18 rests upon and slides in the passage 17, and the 20 pin 20 in the slot 19 pivotally supports the locking plate on the lock casing. As has been stated above, the guideways 32-33 extend into the notches 27-28 and confine the locking bolt. The extent of sliding movement is limited by the pin 20 and corresponding slot 19 and also, in the form shown, 25 by the plug 22 and the corresponding recess 23 in the locking bolt.

When the parts are in the full-line position shown in Fig. 1, the dead bolt mechanism 30 is locked and a key may be inserted in the plug 22, and when the latter is rotated the pin 24, acting against the surface 25 of the locking bolt, serves to retract the latter. When the locking bolt 18 has been retracted 35 to substantially its rear limit, the spring 30, which, as will be observed, is at one side of the locking bolt, serves to bias the latter toward the right as viewed in Fig. 2, and upwardly as viewed in Fig. 1, so as to cause 40 the shoulder 35 on the lock case to engage behind a part of the offset portion of the locking bolt adjacent the notch 27 and thereby latch the same in retracted position. The retracted latched position is shown in dot 45 and dash lines in Fig. 1. The spring then serves not only to bias the locking bolt over, so as to latch the same, but also serves to force the locking bolt outwardly when said locking bolt is released. As soon as the 50 locking bolt is latched in retracted position the plug 22 may be rotated back and the key removed. With the locking bolt retracted and biased and latched in the retracted position (dot and dash lines), it will then be possible to rotate the handle 8 counterclockwise sufficiently to withdraw the dead bolt or bolts, so as to permit the door to be 55 opened without disturbing the then retracted locking bolt 18. An extreme counterclockwise movement will cause the projection or flange 14 to act on the shoulder 36 on the extreme forward end of the locking bolt 18, so as to dislodge the latter from its latched position, so that it will spring forward slightly and stand in such a position

that when the plate 7 is turned so as to again lock the door by means of the dead bolt or bolts, the locking bolt may then automatically spring forward and thereby lock the dead bolt mechanism. 70

It will thus be seen that when a door is equipped with locking means as herein described, it is possible to unlock the door by means of a key, which may then be withdrawn. It is not necessary to have the key 75 when it is desired to again lock the door, since, by an extreme counterclockwise movement of the handle 8, the locking plate is unlatched and held in readiness to move forwardly when the plate 7 is rotated to lock 80 the dead bolts and when the dead bolts are thrown into locking position by the locking plate the latter and the dead bolts, are securely locked in position by means of the forward end 26 of the locking bolt engaging 85 behind the detent or shoulder 15.

While one preferred form of the invention has been described in detail, I do not wish to be limited to the form shown, since 90 the same is but illustrative and many changes may be made within the scope of the invention as defined in the appended claims. 95

I claim:

1. In a lock for a locker door or the like, 95 a locking plate controlling a dead bolt, a lock casing carrying a cylinder plug, a locking bolt pivotally and slidably supported by said lock casing, said cylinder plug having means for retracting said locking bolt, said locking bolt and lock casing having co-acting means for latching the locking bolt in retracted position, and a spring for biasing said locking bolt so as to cause the same to engage said lock casing to hold the locking bolt in retracted position, said locking plate having means for disengaging said locking bolt from said retracted latched position, said locking bolt when in the forward position engaging behind a shoulder 100 on the locking plate for holding the same and the dead bolt controlled thereby in 105 locked position.

2. In a lock, a locking plate controlling a dead bolt, a locking bolt, said locking bolt when in the forward position engaging said locking plate for holding the same in locked position, key-controlled means for retracting said locking bolt, shouldered means for latching said locking bolt in retracted 115 position, and a biasing spring for urging said locking bolt into latched position when retracted, said locking plate having means for unlatching said locking bolt so as to permit same to move outwardly into locking 120 position.

3. In a lock, a locking plate controlling a dead bolt, a lock casing, a locking bolt pivotally and slidably mounted in said lock casing, key-controlled means for retracting 125

5 said locking bolt, a shoulder on said lock casing behind which a part of said locking bolt engages so as to hold the latter in retracted position, and a biasing spring for urging said locking bolt into position behind said shoulder, said locking plate having means for moving said locking bolt out of engagement with said shoulder so as to permit the same to move outwardly to lock 10 said locking plate.

4. In a door lock, a dead bolt therefor, means to move the same into locking and unlocking position, a spring projected locking bolt coacting with the means for moving the dead bolt to hold the latter in locked position, key controlled means for retracting the locking bolt, means for engaging said locking bolt to hold it in retracted position, and means operable by the means for moving the dead bolt to disengage the locking bolt to permit the locking bolt to move into position to lock the dead bolt moving means. 15

5. In a lock, a locking plate having a locking detent thereon, a lock casing, a locking bolt movable thereon, said lock casing and locking bolt having means for latching the locking bolt in retracted position, and means for retracting said locking bolt and urging the same into retracted and latched 20 position, said detent on said locking plate serving when moved into engagement with said locking bolt to unlatch the same and when moved back serving to permit said locking bolt to engage therebehind and lock 25 said locking plate.

6. In a door lock, a hand operated dead bolt means for the door, a key operated locking bolt coacting with the dead bolt, said locking bolt being slidably and pivotally 30 mounted, a spring for projecting the locking bolt, and means for engaging the locking bolt when retracted to hold it against the projecting action of the spring when the dead bolt for the door is retracted, said dead bolt 35 means coacting with the locking bolt to release the latter to permit it to be moved under the action of the spring into position to lock said dead bolt.

7. In a lock, a locking plate having a projection thereon, a locking bolt, key-controlled means for retracting said locking bolt, latch means for holding said locking bolt in retracted position, and resilient means for biasing said locking bolt into latched retracted position, said locking bolt at the forward end having a shoulder thereon to be engaged by said projection on said locking plate for releasing said locking bolt from retracted latched position, whereby 40 upon reverse movement of said locking plate said locking bolt may be moved forwardly to lock the locking plate in locked position.

8. In a lock, a locking plate controlling a dead bolt, a lock casing, a locking bolt 45 pivotally and slidably engaged with said

lock casing, a cylinder lock having a plug for retracting said locking bolt, latch means for holding said locking bolt in retracted position, and resilient means for biasing said locking bolt into latched position, said locking plate having means for releasing said locking bolt from latched position so as to permit said locking bolt to move forwardly to lock said locking plate when the latter is moved to locked position. 75

9. In a lock, a lock casing, a locking bolt slideable and movable edgewise therein, means for retracting said locking bolt, latching means for holding said locking bolt in retracted position when the latter has been retracted and moved edgewise therein, a spring means for urging said locking bolt edgewise into engagement with said latching means to hold the locking bolt retracted, and a dead bolt movable independently of the locking bolt with means for moving said dead bolt, said means also coacting with the locking bolt to release the same from its retracted position when the dead bolt has been retracted. 90

10. In a door locking device of the character described, including a dead bolt, a separate lock for said dead bolt including a locking bolt, key actuated means for retracting said locking bolt to free the dead bolt, means to latch back the locking bolt in retracted position to leave the dead bolt free to be projected and retracted, said dead bolt coacting with said locking bolt to trip the latter when the dead bolt has been retracted with a spring to project the locking bolt when the latter has again been projected. 95

11. In a door locking device of the character described, a door locking means, a separate lock for said door locking means including a spring projected locking bolt for holding the door locking means in locked position, a shoulder independent of the door locking means arranged to engage the locking bolt to hold it retracted, said door locking means coacting with said locking bolt to disengage it from said shoulder when the door locking means is moved to the door unlocking position, and means to cause said locking bolt to move forwardly to engage and hold the door locking means in locked position when released by the latter. 105

12. In a lock for a locker door, a manually operable dead bolt for the door, a key operable locking bolt separate from the dead bolt but coacting therewith and adapted to lock the same in its door locking position, key actuated means to retract the locking bolt, means to latch the latter in its retracted position, and a spring for projecting the locking bolt when the same has been unlatched, said dead bolt coacting with the locking bolt to unlatch the same when the dead bolt has been thrown to its door un- 115 120 125 130

locking position and said locking bolt co-acting with the dead bolt when the latter has been again projected.

13. In a door locking device of the character described, door locking means, a separate lock for said door locking means including a locking bolt, means for retracting said locking bolt to the unlocked position, and latching means for holding said locking bolt in retracted position, said door locking means being positioned to trip said latching means by the retraction of the door locking means to permit said locking bolt to move forwardly to lock said door locking means in locked position when the latter has been again projected to that position.

14. In a locker door lock, a dead bolt therefor, manually controlled means for operating the same, a separate lock for said dead bolt including a locking bolt and key controlled means for retracting the same, spring mechanism for projecting the locking bolt to cause the same to engage and hold the dead bolt in its door locking posi-

tion, and means independent of the dead bolt and its operating means arranged to engage the edge of the locking bolt to hold it retracted, said dead bolt operating means being arranged to engage the locking bolt to free it after the dead bolt has been fully retracted, to permit said locking bolt to move to the dead bolt locking position under the influence of said spring.

15. In a lock for doors and the like, a dead bolt, manually operable means to move the same to and fro, a spring projected locking bolt for locking said means in the dead bolt locking position, a key controlled means to retract said locking bolt, and means to latch said locking bolt in its retracted position, said manually operable means co-acting with said locking bolt to free the same from said latching means after the dead bolt has been withdrawn, whereby said locking bolt may automatically move to its locking position when the dead bolt has again been advanced to lock the door.

NORMAN B. HURD.

Certificate of Correction.

It is hereby certified that in Letters Patent No. 1,566,013, granted December 15, 1925, upon the application of Norman B. Hurd, of New Britain, Connecticut, for an improvement in "Locks," an error appears in the printed specification requiring correction as follows: Page 3, line 102, claim 10, after the word "bolt" insert the words *to lock the dead bolt*; and that the said Letters Patent should be read with this correction therein that the same may conform to the record of the case in the Patent Office.

Signed and sealed this 26th day of January, A. D. 1926.

[SEAL.]

WM. A. KINNAN,
Acting Commissioner of Patents.
